SHORT WAVE DETECTOR

Ernest G. Linder, Philadelphia, Pa., assignor to
 Radio Corporation of America, a corporation of
 Delaware

Application December 31, 1935, Serial No. 56,940

10 Claims. (Cl. 250—27)

The present invention relates to means for detecting ultrashort radio waves and has for its primary object to provide an improved means for that purpose.

5 It is a further object of the present invention to provide an ultrashort wave detector embodying electric discharge apparatus having means for producing a stream of electrons and means for causing a deflection of the electron stream in 10 response to acceleration and deceleration by means under control of an improved ultrahigh frequency modulated carrier wave.

Ultrahigh frequency detector systems have been proposed heretofore embodying an electron 15 stream, but such systems have further included means for deflecting the electron stream or varying the rate of flow of the stream as in the usual radio tube having a control grid and each of such systems had certain limitations. In accordance 20 with the present invention, however, the speed of electron flow in an elongated electronic path is varied through a deflecting electromagnetic or electrostatic field of fixed area, intensity and position, and under control of a received carrier wave. With this arrangement, an electron 25 beam may be caused to be deflected as a result of a variation in speed of flow. The beam is simultaneously deflected with the acceleration and deceleration of the electrons.

30 The invention will, however, be better understood from the following description when considered in connection with the accompanying drawing and its scope will be pointed out in the appended claims.

35 In the drawing, Figure 1 is a schematic circuit diagram of ultrashort wave or high frequency detector means embodying the invention, and

Figs. 2 and 3 are similar schematic diagrams of modifications of the invention as shown in 40 Fig. 1.

Referring to Fig. 1, 5 indicates the evacuated envelope of a cathode ray device having an electron gun as a source of electrons 6, at one end of the envelope, and a plurality of closely spaced 45 targets or anodes 7, 8 and 9 at the opposite end of the envelope toward which an electronic stream or beam, indicated by the dotted line 10, is projected from the source 6. Between the source 6 and the anodes and more adjacent to the latter 50 the electron beam is subjected to a relatively strong electrical field such as an electrostatic field provided by two electrostatic deflecting plates 11 to which are connected terminal leads 12 for the application of deflecting potentials. The strength 55 of the field is adjusted in such a manner that

electronic stream has sufficient velocity to follow the dotted path 10 and a continuation thereof indicated at 13 to normally strike a central target 8.

In systems heretofore known, signal strength variation has been utilized to cause a variation in 5 the potentials of the deflecting plates or of similar electrodes spaced along the electronic stream to cause a deflection thereof to actuate an amplifier as an output device. In the present example, an electric discharge amplifier stage is provided in 10 connection with the detector, and includes an electric discharge tube 14 having a cathode 15, a control grid 16 and an output anode 17, the latter being coupled to a suitable audio frequency output circuit 18 through a coupling transformer 15 19 in the anode output circuit 20.

The amplifier control grid 16 is arranged for self bias operation and is connected through an input circuit with a grid resistor 21 through which bias potentials are supplied to the grid. The 20 cathode end of the bias resistor 21 is connected to the central anode 8 while the grid end of the resistor 21 is connected as indicated with the adjacent anode electrodes 7 and 9.

With a constant electrostatic field supplied by 25 the electrodes 11, a variation in the velocity in the electron beam, for example, a reduction in velocity, causes the beam to be deflected simultaneously to a greater or lesser degree under the influence of the electrostatic field, as indicated 30 by the dotted paths 22, the direction of deflection depending upon the polarization of the plates and in any case will be in but one direction. If modulation is present, the same is transferred to the grid impedance 21 and is amplified in the device 14, as is well understood.

In order that the velocity of the electron beam may vary in response to a received signal wave, a transmission line is provided adjacent to and 40 extending along the electron beam, as indicated by the conductors 23 and 24, each of which is connected with a short wave antenna at the end more adjacent to the cathode or electronic gun 6. In the present example, the antenna includes a divided half wave wire 25—26 extending through 45 the envelope of the device for collecting radiated energy.

Radiation received by the antenna causes 50 standing waves to be formed on the transmission line, along which are spaced a plurality of pairs of grids 27, one grid of each pair being connected with one of the leads 23 and 24 forming the transmission line. The grids in any pair are arranged closely together, at a distance which is relatively short in comparison with the wave 55

length of the carrier wave to be received, and preferably less than one tenth of the length of said carrier wave. Furthermore, the spacing of the pairs of grids along the transmission is preferably some multiple of a half wave, as the detector system shown is most effective for the reception of micro waves, such as those below ten centimeters in length or above 3,000 megacycles in frequency.

- 10 The grids are arranged preferably in the form of loops or circular coaxial rings, as shown, through the center of which the electronic stream is projected. The characteristics of the line, such as the inductance of the leads 23 and 24, are so 15 adjusted, that the average electron speed may equal or closely approximate the speed of propagation of the received wave along the transmission line. The electrostatic field is adjusted to a fixed 20 value so that in the absence of a signal or carrier wave the electron beam strikes the central anode. With the beam directed along the axis of the transmission line and through the grids, as shown, in the presence of a signal or carrier wave, the 25 electrons are accelerated or decelerated successively at each pair of grids, if the electron velocity approximates that of the wave propagation. The net acceleration is translated into transverse spread of the beam as the beam passes through the transversely acting fixed electrical field.

The beam is collected on the set of three adjacent anodes which are closely spaced, the two outer anodes being connected together. In the 35 present example, when a signal is received, the beam spreads as shown in response to deceleration and more current is received by one or the other of the electrodes, depending upon the polarity of the plates 11, and if carrying modulation, the same is amplified and transferred to the output 40 circuit 18.

It is necessary to bend or deflect the electronic stream or beam in the transverse deflecting field and to provide a strong field in order that a low 45 percentage variation in speed of the beam may be effective to cause the beam to sweep across the electrodes. This permits the sensitivity of the detector to be made relatively high and is desirable for the reason that the speed variation is in any case a relatively small percentage of the 50 average speed of the stream. For the foregoing reasons, the present device may be considered as a variable velocity detector.

It is desirable to reduce the speed of propagation of the wave along the transmission line and, 55 in Fig. 2, a system modified to provide the above feature is shown. In this figure, the same reference numerals are used to refer to the same parts as provided in the circuit of Fig. 1.

Referring to Fig. 2, a curved envelope 30 is provided so that the electron beam 10 from the electron gun 6 is caused to strike the central anode 8 by reason of deflection through a transversely acting magnetic field indicated by the cross hatched area 31. The strength of the field is such 65 that the beam assumes the curved initial path 32 normally to strike the electrode 8, as shown. As signals are received on the antenna 25-26 and transmitted along the transmission line and, 70 the grids 27, acceleration of the stream will cause the speed to increase and the electron beam to shift to the outer anode 7 along a path generally indicated at 33, while a decrease in the acceleration and speed of the electrodes will cause the 75 stream to shift to the inner electrode 9 along a

path generally indicated at 34, the curvature taking place only in the magnetic field.

In order to cause the wave propagation to be reduced in speed, thereby to avoid excessive electron speeds, a few inductive turns 35 may be introduced into the transmission line between the pairs of grids, as indicated.

By means of the spaced pairs of grids connected with and positioned along a transmission line adapted for sustaining standing waves, the 10 electrons are accelerated and decelerated in response to carrier waves to cause operation of the detector, as distinguished from systems heretofore known wherein the electron beam is deflected in response to signals applied to plates 15 arranged along the path of the beam, and acting at right angles thereto. Further, as shown in Fig. 2, in order that slight variations in speed may cause a wide deflection of the beam at the target 20 end of the cathode ray device, the beam is preferably initially deflected through a fixed field, such as a magnetic field acting transversely with respect to the beam.

As in the previous embodiment of the invention, the anodes are connected with a suitable 25 audio frequency amplifier 36.

Referring now to Fig. 3, in which the same reference numerals are used for like circuit elements and parts, as in Fig. 2, it will be seen that the electron discharge or cathode ray device is 30 further curved and is arranged to provide substantially a 180° change in direction, in a semi-circle, the circular portion lying in an enlargement of the magnetic field, as indicated at 40. All of the elements are the same as in the preceding figure except that the inductance of the transmission line is depended upon to prevent the 35 velocity of wave propagation from reaching excessive limits. It is desirable, however, to thus increase the length of the electronic stream and the magnetic field may be made larger in extent than would otherwise be permissible. Furthermore, space is conserved by the curved construction shown. The operation is the same as described in connection with the preceding figures. 45

As shown in Fig. 3, the electronic beam is deflected through an arc of a circle by a relatively large area magnetic field whereby the length of the beam acted on by the field is greater and the control of the speed of the electrons is more 50 effective.

From the foregoing description, it will be seen that it is desirable to increase the length of the electronic path or the length of the beam and the transmission line, as well as the area of the transversely acting electromagnetic or electrostatic field and to cause the beam initially to be deflected so that the acceleration and deceleration of the electrons may simultaneously cause a deflection of the beam. It will be seen that the sensitivity of the detector may be increased by increasing the strength of the field and by providing the series of grids spaced along the beam in conjunction with the initial deflection. No complicated means is required for conveying or translating signal variations into variable 60 electrical potentials or fields for deflecting the beam, as has heretofore been necessary.

The detector, as shown and described, may be considered as a variable velocity detector in 70 which an electronic beam is deflected by accelerating and decelerating the electrons, the deflection and acceleration and deceleration being simultaneous.

I claim as my invention:

1. Ultrashort wave radio detector comprising, in combination, means for producing an electron beam, a plurality of anode electrodes for receiving said electron beam and deflections thereof, and means responsive to a received carrier wave for changing the axial speed of flow of said electrons and the transverse deflection of the beam, whereby differing anode electrodes are traversed by said beam. 5
- 10 2. Ultrashort wave radio detector comprising, in combination, means for producing an electron beam, a plurality of anode electrodes for receiving said electron beam and deflections thereof, and means responsive to a received carrier wave for changing the speed of flow of said electrons and the deflection of the beam, whereby differing anode electrodes are traversed by said beam, said last named means including a plurality of coaxial grid electrodes arranged in pairs along said beam, whereby said beam passes through successive pairs of grids, a carrier wave transmission line extending along said beam to which said grids are connected and a constant electrical field acting transversely with respect to said beam over a portion of the length of said beam sufficient initially to deflect it and to provide a fixed field through which the beam is further deflected simultaneously with acceleration and deceleration of the electrons in said beam. 15
- 20 25 30 3. Ultrashort wave radio detector comprising, in combination, means for producing an electron beam, a plurality of anode electrodes for receiving said electron beam and deflections thereof, a modulation system amplifier connected with said electrodes, means for deflecting said beam in response to variations in speed of electron flow therein, and means providing a transmission line extending along said beam, energy collecting means connected with said line, and a plurality of grid electrodes arranged in pairs along said beam and connected alternately to opposite sides of said transmission line, said pairs being spaced apart along the electronic beam and transmission line at distances which are a multiple of a half wave, and said grids in any pair being arranged relatively closely together. 35
